UNITED STATES PATENT OFFICE.

ROBERT G. MITCHELL, OF MOUNT VERNON, NEW YORK.

GLASS-HOLDER.

1,397,328.

Specification of Letters Patent.

Patented Nov. 15, 1921.

Application filed April 27, 1921. Serial No. 464,984.

To all whom it may concern:

Be it known that I, ROBERT G. MITCHELL, a citizen of the United States of America, residing at Mount Vernon, Westchester county, New York, have invented a new and useful Glass-Holder, of which the following is a specification.

My invention relates to holders for drinking cups or tumblers and the like. My object is to provide a simple and inexpensive holder into which a glass may be easily inserted, and which cup when in place will be held firmly and yet in such a manner as to eliminate any danger of breakage due to 15 improper or uneven pressure thereon.

Another object is to provide a holder which may be easily adjusted to fit cups of different sizes and which to a large extent is, in fact, self-adjusting. 20 In the accompanying drawings, I have shown my invention in one preferred form only, appreciating that various changes may be made without departure from the spirit and scope of the invention.

25 In the drawings:

Figure 1 is a perspective view of the holder, a tumbler being indicated in dotted outline.

Fig. 2 is a side elevation of the holder.

30 Fig. 3 is a plan view thereof.

In the particular form of my invention shown, the holder is constructed from a plain flat strip of metal. I take such a strip and slit it at one end and then spread apart 35 the ends on each side of the slit and bend portions of said ends upwardly to form supporting arms for the forward or front side of the cup. The opposite end of the strip is bent up in such a manner as to form a 40 combined handle and a third cup supporting arm for the rear side of said glass. These three supports coöperate to hold the cup in the manner shown. It will be noted that the free lower end of the third cup-supporting 45 arm extends down into a plane below the top of the front supporting arms, so as to overlap the same; hence a cup will not be displaced by a mere rocking movement but must be withdrawn by a longitudinal sliding 50 movement.

Describing specifically the particular construction shown in the drawings, 1 represents the bottom of the holder. 2—2 represent the two upwardly projecting supporting 55 arms for supporting the forward portion of the cup. 3 represents the grip portion or

handle which projects upwardly from the back of the base 1. 4 represents the third supporting arm for the rear of the cup. This arm projects downwardly from the 60 upper end of the handle 3. By reason of the unique mounting of the arm 4 it is apparent that this member is capable of tilting or rocking so that it may automatically adjust itself to bear with a substantially even pressure 65 throughout its length against the side of the cup. This arm 4 therefore functions after the manner of a spring follower which tends to push the cup forwardly against the arms 2—2. By reason of the unique supporting arm construction, the pressure 70 against the side of the cup is substantially uniform throughout the length of the arm, that is to say, there is no tendency to grip the cup more tightly at the bottom than at 75 any point above the bottom, hence the danger of glass breakage, so common in holders in which a progressive wedge action occurs as a glass is inserted, is entirely eliminated. By this arrangement assuming the holder 80 is adjusted for a given size of glass, it will readily automatically adjust itself to an over-sized glass, by which I mean a glass which is accidentally somewhat larger than the set to which it belongs. It will be noted 85 that the bend α where the handle meets the base, is set back further from the axial center of the glass than the bends y — y at the base of the arms 2—2. This results in a two fold advantage. First, it increases the 90 effective supporting area of the base giving great stability to the holder, and again it permits the holder to be adjusted to receive cups of larger diameter than the ones shown in the drawings. If a glass of larger diameter 95 is to be employed, the user simply bends back the arm 4 sufficiently to afford adequate room for the larger glass. If desired, part of this room may be provided by bending back the handle 3 as well as the arm 4. 100 It follows that a manufacturer need only make one size of holder for cups of quite a variety of sizes. It is preferable that the base at its corners α — y — y should be bent down slightly so that the holder will rest on 105 a table or counter on three points of support all spaced well apart. By my improvement the grip 3 is of the long approved and conventional form best adapted to safe handling. The device has no projections or extensions of an awkward nature that tend 110 to invite capsizing. The device is easily

adjusted to receive cups of different design by simply bending the supporting arms 2—2—4, so that they will conform approximately to the pitch of the sides of the cup, 5 that is to say, some cups have very little taper or flare, others have more flare. The holder is very easily adjusted to these differences in cup design without the exercise of any special skill. When the holder is 10 made from a single strip of metal, it will be noted that each of the forward arms 2—2 will be of a cross section equal to one-half of the cross section of the rear supporting arm 4. It is obvious that if the arm 4 was formed 15 at the back of the base so as to project upwardly therefrom in a manner corresponding to either of the arms 2—2, it would be too rigid. By my construction, however, the flexibility of the arm 4 is increased by reason of the fact that it does not project directly up from the base 1, but on the contrary, projects downwardly from the upper part of the flexible grip portion 3, hence, even though the combined grip and third 20 supporting arm are of a greater cross section than the forward arms 2, the said third arm is easily flexed by the cup and will not press against the latter unduly or with any strain that tends to invite breakage. 25

30 By the term cup as used herein, I mean of course to include any cup, receptacle or support which may be advantageously used with the holder, such as a receptacle for supporting a paper cup.

35 I claim:

1. A cup holder comprising a base, two upwardly-projecting arms at the forward part of said base arranged to engage the forward side of a cup, a third arm arranged to 40 engage the rear side of a cup, said third arm overlapping the first-mentioned arms, and a support for said third arm extending upwardly from said base, said third arm being located between said support and said 45 first-mentioned arms, the lower part of said third arm being free to flex to and fro.

2. A cup holder comprising a base, means at the forward part thereof for engaging and supporting the front side of a cup, a 50 flexible handle projecting upwardly from the base at the rear thereof, and a third cup-engaging arm connected to said handle adjacent its upper end and extending downwardly in front thereof to engage the rear 55 side of a cup, the lower end of said third arm being free to flex to and fro.

3. A cup holder comprising a base, two upwardly projecting spaced spring arms at the forward part of said base arranged to 60 engage a cup at its forward side, a handle bent upwardly from said base at the rear thereof, a glass-engaging arm flexibly carried by the upper part of said handle and extending downwardly from the upper part 65 of said handle and overlapping the first-

mentioned arms and located between said first mentioned arms and said handle.

4. A cup holder comprising a strip of metal forked at its forward end, the forked portions diverging at the base, the ends of 70 said forked portions being bent upwardly to form supporting arms for the forward side of a cup, the rear part of said strip being bent upwardly, forwardly and downwardly to a point below the tops of the first- 75 mentioned arms and forming a combined handle and third supporting arm for the rear of said cup and forward of the handle portion, all of said arms and said handle being yielding, the lower part of said third 80 arm being free to flex to and fro.

5. A cup holder comprising a strip of metal forked at its forward end, the forked portions diverging at the base, the ends of 85 said forked portions being bent upwardly to form supporting arms for the forward side of a cup, the rear part of said strip being bent upwardly, forwardly and downwardly to a point below the tops of the first-mentioned arms and forming a combined 90 handle and third supporting arm for the rear of said cup and forward of the handle portion, all of said arms and said handle being yielding, the lower part of said third arm being movable to and fro, the bend at 95 the lower end of the handle being more remote from the axial center of the cup support proper than the bends at the foot of the upwardly projecting arms.

6. A cup holder comprising a base, two 100 upwardly projecting arms at the forward part of said base, said arms being free at their upper ends, and a handle projecting upwardly from the base at its rear and a third supporting arm projecting forwardly 105 toward the two first-mentioned arms and downwardly from the upper part of said handle to a point below the tops of the first-mentioned arms, the lower part of said third arm being free to flex.

7. A holder of the character described, comprising a base formed of a strip of metal forked at one end, the forked ends diverging and being bent upwardly to form spaced supports for the front part of the cup, the 115 rear unforked portion of said strip being bent upwardly to form a flexible handle, the upper end of said handle portion being bent forwardly toward the front supporting arms and downwardly to form a third cup-supporting arm, the lower end of said last-mentioned arm projecting into a plane below the upper ends of the front supporting arms and being free to move bodily to and fro to operate as a spring follower to press a cup 120 forwardly against the two first-mentioned arms.

8. A holder for drinking cups and the like, comprising a base, an upwardly projecting arm or support for the front side of 125

65 of said handle and overlapping the first-

a cup, another upwardly projecting arm or support for the rear side of a cup, one of said supports being flexible and having its upper portion extended inwardly and downwardly and being free at its lower portion to form a flexible downward extension.

9. A holder for drinking cups and the like, comprising a base, an upwardly projecting arm or support for the front side of a glass, and another upwardly projecting

arm or support for the rear side of a glass, one of said supports being flexible and having its upper portion extended inwardly and downwardly to form a flexible downward extension the lower part of which is movable 15 to and fro, the upwardly projecting portion of the last mentioned support being set back to form a handle.

ROBERT G. MITCHELL.
